Patented Aug. 12, 1913.

UNITED STATES PATENT OFFICE.

JAMES MACDONALD, OF NEW YORK, N. Y.

PAPER-FILE.

1,069,711.

Specification of Letters Patent. Patented Aug. 12, 1913.

Application filed February 21, 1912. Serial No. 679,024.

To all whom it may concern:

Be it known that I, JAMES MACDONALD, a subject of the King of Great Britain, and a resident of the city of New York, borough 5 of Manhattan, in the county and State of New York, have invented a new and Improved Paper-File, of which the following is a full, clear, and exact description.

The object of the invention is to provide 10 a new and improved paper file arranged to permit of conveniently placing bills, letters and other papers or documents in position on the file, or to allow removal of any one of the papers from the file for reference or 15 other purposes and without disturbing the remaining papers on the file.

For the purpose mentioned use is made 20 of a holder formed from a single piece of sheet material bent to provide a back and a front, the latter extending upwardly and outwardly from the lower end of the back to permit of placing papers between the front and back, the said front having a rearwardly and downwardly-extending 25 spring tongue adapted to press the filed papers against the said back.

A practical embodiment of the invention 30 is represented in the accompanying drawings forming a part of this specification in which similar characters of reference indicate corresponding parts in all the views.

Figure 1 is a perspective view of the paper file; Fig. 2 is a transverse section of the same; Fig. 3 is an enlarged face view of 35 one of the holders of the paper file, the dotted lines showing the manner of connecting one holder with another, and Fig. 4 is a cross section of the same.

The paper file, as illustrated in Figs. 1 40 and 2, consists of a series of holders A, A', A² arranged one below the other and detachably connected with each other, as hereinafter more fully explained. Each of the 45 holders A, A', A² is made from a single piece of sheet metal or other suitable material, bent to provide a back B and a front C, the latter extending from the lower end of the back B in an upward and forward direction so as to permit of placing bills, 50 letters and other papers or documents in position between the front C and the back B.

The front C is provided with an integral struck-up tongue D extending rearwardly and downwardly to press the inserted papers 55 or documents against the back B of the corresponding holder so as to hold the papers

or documents securely in position on the holder.

The several holders A, A', A² may be fastened to a wall or other suitable support 60 by the use of screws E or other fastening devices, but as the holder A' is hung or suspended from the holder A and the holder A² is hung or suspended from the holder A', it is evident that only the upper holder A 65 needs to be fastened to a suitable support by the fastening devices E.

The back B of each of the holders A, A' and A² is provided near its upper end and at the rear of the back B with a ticket 70 holder F for supporting a ticket G containing the name of a person, firm or corporation, the bills or other papers of which are filed in the corresponding holder A, A' or A². The ticket holder F is preferably an 75 integral part of the back B, and for this purpose an L-shaped supporting member F' is struck up from the back B in a rearward direction for supporting the ticket G, and lugs F² are struck up from the back B on 80 opposite sides of the lug F' to form the sides of the holder F to limit the sidewise movement of the ticket G resting on the lug F'.

The upper ends of the holders A', A² are 85 provided with slots H extending across the back and adapted to be engaged by the lower or bent end of the holder next above so as to support the holder from the one next above. It will be seen that by the arrangement described a hinge connection is had 90 between successive holders to suspend one holder from the next one above, thus permitting of forming the paper file of any desired number of holders, one suspended from 95 the next one above.

The lower portion of the front C slightly projects at the sides C' so that the next lower holder cannot be slipped off the front of the holder next above and only slipped 100 over the back of such holder, and hence when the upper holder is fastened to a wall or other support the remaining holders cannot be surreptitiously removed by unauthorized persons.

The paper file shown and described is very simple and durable in construction, can be cheaply manufactured, and the several holders can be readily assembled for holding papers pertaining to particular business trans- 110 actions.

Having thus described my invention, I

claim as new and desire to secure by Letters Patent:

1. A paper file, comprising a series of holders suspended one from the other, each holder being formed of a single piece of sheet material bent to form a back and a front, the latter extending upwardly and outwardly from the lower end of the back and the said front having a struck-up tongue 10 extending between the front and back, the upper end of the said back having a slot for engagement by the bent end of the next preceding holder above to form a hinge connection between a holder and the one next 15 above, the lower portion of the front projecting at the sides, to prevent a holder being slipped off the front of the holder next above.
2. A paper file comprising a series of holders suspended one from the other each holder being formed of a single piece of sheet material bent to form a back and a front, the upper end of the back of a holder having a slot extending across the holder adjacent to 25 its upper edge and forming a bar at said edge for engagement by the bend at the junction of the front and back of the holder next above, the front of the last mentioned holder being wider than the length of the 30 said slot to prevent a holder being slipped off the front of the holder next above.
3. A paper file comprising a plurality of holders suspended one from the other, each holder being formed of a single piece of 35 sheet material bent to form a back and a front, the latter extending upwardly and outwardly from the lower end of the said back, and the said front having a spring tongue extending rearwardly and downwardly 40 between the said front and back, the

upper holder having means whereby it may be fastened to a support, the suspended holders each having a slot extending across the holder adjacent its upper edge and forming a bar at said edge of the holder, the slot 45 of one holder being adapted to pass over the back of the holder next above to cause the said bar to engage the bend at the junction of the front and back of said holder next above, the front of the holders at the lower 50 portion being wider than the length of the said slots, to prevent a holder being slipped off the front of the holder next above.

4. A paper file comprising a holder adapted to be attached to a support, and a holder 55 adapted to be suspended from the first mentioned holder, the holders each having a front and a back, the front extending upwardly and outwardly from the lower end of the back and having a tongue extending 60 between the front and the back, the last mentioned holder having a transverse slot in its back near the upper edge and forming a bar at said edge, the back of the first mentioned holder being adapted to pass through 65 the said slot, and the said bar being adapted to engage the first mentioned holder at the junction of its front and back to form a hinge connection between the holders, and means for preventing the suspended holder 70 from being slipped off the front of the other holder.

In testimony whereof I have signed my name to this specification in the presence of two subscribing witnesses.

JAMES MACDONALD.
